US00D601712S

(12) **United States Design Patent**
Tajima

(10) **Patent No.:** **US D601,712 S**
(45) **Date of Patent:** **** Oct. 6, 2009**

(54) **CARRIER ENCLOSING TIP**

2008/0257073 A1 10/2008 Tajima

(75) Inventor: **Hideji Tajima**, Matsudo (JP)

(74) *Attorney, Agent, or Firm*—Haynes and Boone, LLP

(57) **CLAIM**

The ornamental design for a carrier enclosing tip, as shown
and described.

DESCRIPTION

FIG. 1 is a perspective view of the carrier enclosing tip showing
my new design;

FIG. 2 is a front elevational view thereof, the rear elevational
view being a mirror image;

FIG. 3 is a top plan view thereof, the bottom plan view being
the same;

FIG. 4 is a left side elevational view thereof;

FIG. 5 is a right side elevational view thereof;

FIG. 6 is a sectional view thereof, taken along line 6—6 of
FIG. 2; and,

FIG. 7 is an enlarged in scale sectional view thereof, taken
along line 7—7 of FIG. 2.

1 Claim, 3 Drawing Sheets
